UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

STEAM-BOILER FURNACE

Application filed August 19, 1925. Serial No. 51,083.

My present invention relates to furnaces particularly adapted for use with steam boilers, and more particularly one in which fuel is burned on a mechanical stoker, especially if the combustion air is supplied under pressure. My invention will be best understood from the following description and the annexed drawings showing an illustrative embodiment of my invention.

10 In the drawings, Fig. 1 is a side sectional elevation on the line 1—1 of Fig. 2 of an illustrative embodiment of my invention with the upper part of the boiler, which may be of any well-known form, broken away, and 15 Fig. 2 is a view from the right of Fig. 1 of a part of the arrangement shown in Fig. 1.

Like reference characters indicate like parts in the different views.

In the arrangement illustrated in the drawings, the furnace chamber is provided with a chain grate stoker 11 which may be provided with ducts (not shown) for supplying air under pressure to the space between the upper and the lower runs of the grate. A 25 combustion arch 12 extends over the front part of the grate 11 and from the inner end of the arch extends upwardly and outwardly the front furnace wall 13. The rear furnace wall 14 has its inner face at the lower part, 30 then extending inwardly or forwardly for a short distance and then diverging outwardly up to the furnace gas exit.

Above the furnace chamber is a water tube boiler of a well-known form with downtake headers 15 and uptake headers 16 connected by water tubes 17. On the lowermost row of water tubes is a longitudinal baffle 18 forming a part of the furnace roof, a baffle 19 extending upwardly from the inner end 40 of the baffle 18 to form with the header 16, an upward pass for the gases across the water tubes. Since my present invention is not concerned with the particular type of boiler used in connection with the furnace, 45 further description of the boiler will be unnecessary.

Extending across the lower part of the rear wall 14 is a header 20 which may be connected to any suitable source of water supply. Connected to the header 20 at their

lower ends and to the mud drum 21 of the boiler at their upper ends is a plurality of curved tubes 22 which are arranged as best shown in Fig. 1, so that the lower part of such tubes projects inwardly and upwardly 55 over the rear end of the stoker 11 and then in a wide sweeping curve up to the mud drum 21, the upper part of the tubes 22 extending across the path of the gases flowing from the stoker into the outlet from the furnace chamber which, of course, is also the inlet to the spaces around the boiler tubes, the baffle 18 directing the gases from the furnace chamber into this outlet.

On the lower part of the tubes 22 is placed 60 a layer of tile forming a furnace arch 23, this arch extending to a point sufficiently high in the furnace chamber to provide a reflecting surface to throw the heat downward on the fuel being burned, the tubes 22 on which 65 the arch 23 is supported serving to keep the arch 23 cool and also, in connection with the arch itself, protecting the rear furnace wall 70 from the intense heat from the fuel.

At the lower end of the arch 23 is a series 75 of chutes 24 conveniently built in the rear wall and connecting with sheet metal hoppers 25, these hoppers having outlet pipes 26. The rear wall is also provided with a series 80 of openings, each with a suitable closure, the 80 openings 27 being located above the lower surface of the arch 23 and the openings 28 extending below the lower end of the arch 23, so that by the former openings, access to the 85 upper surface of the arch may be had and through the lower openings, access to the rear end of the grate 11. A dust blower 29 may be located behind the upper part of the arch 23.

With certain grades of fuel, and particularly when burned under pressure conditions, particles are thrown up from the fuel bed which, if permitted to enter among the boiler tubes, become chilled and harden thereon to form a slag deposit. With the arrangement 90 which I have described, these particles, in passing between the tubes 22, will be somewhat cooled and will have a tendency to fall out of the gas stream onto the upper surface 95 of the arch 23, this falling out being assisted 100

by the form of furnace chamber which, it will be noted, is wide at the bottom and at the top with a constricted throat at about its mid-section. This form of chamber creates a 5 thorough mixture and a turbulence in the gas streams, so that not only is better combustion produced, but the solid particles are given a direction of motion other than upward, so that they may strike against the rear wall and 10 fall to the arch 23.

The dust and slag particles which have been made non-adherent by their chilling in passing between the tubes 22, will accumulate on the top of the arch 23 and slide into the chutes 15 24 and the hoppers 25. The blower 29 may be used to assist the cleaning of the arch 23 and if for any reason there is an accumulation which it is difficult to remove by means of the blower 29, the openings 27 afford means 20 by which such deposits may be drawn into the chutes 24 by any suitable tool.

By giving the tubes 22 the long, easy reversed curve shown, the tube is not only carried well out into the combustion chamber 25 into the desired position for supporting the arch 23, but it will also permit motion of the boiler with respect to the box 20 without straining the connections between the tubes 22 and the header 20 and mud drum 21.

30 It will be understood that the arrangement which I have described is merely illustrative and that the embodiment of my invention may be widely varied. It will further be understood that some of the features of my invention may be used independently of other features.

I claim:—

1. In a boiler furnace, a stoker and a stoker arch at the rear of the furnace chamber, said 40 arch comprising a plurality of tubes extending along a wide sweeping curve from the lower rear part of the furnace chamber forwardly and upwardly into the furnace chamber and then rearwardly and upwardly with 45 their upper ends connected to the boiler spaces, and tile supported on the lower portions of said tubes and extending from the rear furnace wall into the furnace chamber, said tubes being spaced apart to permit the 50 furnace gases to rise between the portions of said arch tubes above the tile.

2. In a boiler furnace, a stoker and a stoker arch at the rear of the furnace chamber, said arch comprising a plurality of tubes extending along a wide sweeping curve from the lower rear part of the furnace chamber forwardly and upwardly into the furnace chamber and then rearwardly and upwardly with 55 their upper ends connected to the boiler spaces, tile supported on the lower portions of said tubes and extending from the rear furnace wall into the furnace chamber, said tubes being spaced apart to permit the furnace gases to rise between the portions of said 60 arch tubes above the tile, dust chutes in the

rear furnace wall to receive dust collecting on the upper surface of said tile, and openings in said furnace wall through which access may be obtained to said tile.

3. In a boiler furnace, a stoker and a stoker arch at the rear of the furnace chamber, said arch comprising a plurality of tubes extending along a wide sweeping curve from the lower rear part of the furnace chamber forwardly and upwardly into the furnace chamber and then rearwardly and upwardly with 70 their upper ends connected to the boiler spaces, tile supported on the lower portions of said tubes and extending from the rear furnace wall into the furnace chamber, said tubes being spaced apart to permit the furnace gases to rise between the portions of said arch tubes above the tile, dust chutes in the rear furnace wall to receive dust collecting on the upper surface of said tile, and a soot blower to blow the dust along the upper surface 75 of the tile into said chutes.

4. In a boiler furnace, a stoker, a furnace roof arranged to direct the gases from the stoker to a gas outlet at the rear part of the top 80 of the furnace chamber, a stoker arch at the rear of the furnace chamber, said arch comprising a plurality of tubes extending in a curve from the lower rear part of the furnace chamber forwardly and upwardly into the furnace chamber and then rearwardly and upwardly with 85 their upper ends connected to the boiler spaces, and tile supported on the lower portions of said tubes and extending from the rear furnace wall into the furnace chamber, said tubes being spaced apart to permit the furnace gases to rise between the portions of said tubes above the tile are in the path of the gases flowing to said gas outlet.

5. A boiler furnace having the top and the 90 bottom of the chamber larger than the mid-section thereof with the rear and front walls of the furnace chamber inclined toward each other at the lower part of the furnace chamber up to said mid-section and then away 95 from each other above said mid-section, a stoker in the lower part of the furnace, a furnace roof to direct the gases from the stoker to a gas exit at the upper rear part of the furnace chamber, arch tubes extending from the rear furnace wall upwardly and 100 forwardly above the rear of said stoker and then upwardly and rearwardly toward the rear furnace wall with their upper ends connected to the boiler spaces, and tile on the lower portions of said tubes to form an arch over the rear of the stoker, with the top of the arch at said narrow mid-section of the furnace chamber.

6. A boiler furnace having the top and the 105 bottom of the chamber larger than the mid-section thereof with the rear and front walls of the furnace chamber inclined toward each other at the lower part of the furnace chamber up to said mid-section and then away 110

from each other above said mid-section, a
stoker in the lower part of the furnace, a fur-
nace roof to direct the gases from the stoker
to a gas exit at the upper rear part of the fur-
nace chamber, arch tubes extending from the
5 rear furnace wall upwardly and forwardly
above the rear of said stoker and then up-
wardly and rearwardly toward the rear fur-
nace wall with their upper ends connected to
the boiler spaces, and tile on the lower por-
10 tions of said tubes to form an arch over the
rear of the stoker, with the top of the arch at
said narrow mid-section of the furnace cham-
ber, said tubes being spaced apart with their
upper portions extending across the path of
15 the gases flowing to said exit.

7. In a boiler furnace, a chamber having
wide bottom and top portions connected by a
constricted throat, a grate in the bottom por-
20 tion, a plurality of tubes extending into said
bottom portion and upwardly and forwardly
and then upwardly and rearwardly
through said throat toward a wall of the
chamber, whereby the upper portions of the
25 tubes are vertically above the lower portions
thereof, and tile supported on said lower por-
tions of the tubes, whereby slag particles
passing between the upper portions of the
tubes may be guided by said wall through
30 said throat onto said tile.

HOWARD J. KERR.
